GARMENT SUPPORTER

Henry M. Herbener, Thomasville, Ga.

Substituted for abandoned application Serial No. 322,589, March 6, 1940. This application January 29, 1942, Serial No. 428,772

5 Claims. (Cl. 24—263)

My invention relates to garment supporters.

An important object of the invention is to provide a garment supporter, of simplified construction, and which will securely grip the garment, holding the same against accidental displacement.

A further object of the invention is to provide a garment supporter of the above-mentioned character which is convenient and easy to manipulate.

A further object of the invention is to provide a garment supporter so constructed that the pull upon the garment supported will cause an increased gripping action upon such garment.

A further object of the invention is to provide a device of the above-mentioned character which is thin and flat, and which may be manufactured cheaply.

Further objects and advantages of the invention will be apparent during the course of the following description.

This application is a substitute for my abandoned application for Garment supporter, filed March 6, 1940, Serial No. 322,589, allowed July 30, 1940.

In the accompanying drawing forming a part of this application and in which like numerals are employed to designate like parts throughout the same:

Figure 1 is a side elevation of a garment supporter embodying my invention, showing the grip element in the lowered holding position.

Figure 2 is a vertical section taken on line 2—2 of Figure 1.

Figure 3 is a similar view with the grip element in the inactive position.

Figure 4 is a horizontal section taken on line 4—4 of Figure 1.

Figure 5 is an enlarged section taken on line 2—2 of Figure 1, and,

Figure 6 is a side elevation of the grip element removed.

In the drawing, wherein for the purpose of illustration, is shown a preferred embodiment of my invention, the numeral 10 designates a closed frame or loop which is preferably flat. The frame 10 is preferably tubular and may be formed of sheet metal or any other suitable material. The sheet metal is bent into the tubular form, such as rectangular in cross-section, affording inner flanges 11, which contact throughout the major portion of the sides of the frame or loop and throughout the upper ends of the frame or loop. The flanges 11 upon the sides of the frame or loop are bent inwardly for short distances,

providing slots 12. The upper end of the frame or loop 10 is suitably secured to a supporting element 13, which may be an elastic band. The flanges 11 terminate at the lower end of the frame or loop 10, and the lower end of the frame or loop is U-shaped in cross-section or channel-shaped in cross-section. The lower end of the frame or loop 10 receives within its channel a stationary pad or block 14, formed of rubber and which is held in place by inwardly pressed beads 15. An upstanding flange 16 is formed upon the lower end of the frame or loop and projects above the pad or block 14 and the flange 16 is arranged upon that side of the frame remote from the wearer. A short upstanding flange 17 is also provided and is disposed upon that side of the frame next to the wearer.

The numeral 18 designates a grip element, having a jaw 19, to enter the lower end of the frame or loop 10, and press the garment against the block or pad 14. The grip element is provided at its top with a pivot element 20, preferably formed integral therewith, and the ends of this pivot element extend through the slots 12 into the bore of the sides of the tubular frame or loop. The end walls of the slots 12 form stops to limit the up and down movements of the grip element. The pivot element 20 is provided at its ends with heads 21, to prevent the pivot element from being withdrawn through the slots 12. The slots 12 limit the downward movement of the grip element 18, as stated, but the grip element may move downwardly sufficiently to firmly press the garment against the pad 14, and upwardly sufficiently to clear the flange 17.

In use, if the device is employed to support a hose, the supporter is arranged in the proper position upon the wearer, and the flange 16 is upon that side of the frame or loop remote from the wearer. The grip element 18 now occupies the lowered inactive position, as indicated in dotted lines in Figure 2. The top of the hose is passed over the grip element 18. The hose is then pressed against the grip element and held in engagement therewith by the finger while the grip element is turned counter-clockwise, Figure 3. The hose becomes folded over the jaw 19 of the grip element and over the top of the grip element, when the grip element again assumes the lowered position next to the wearer. The grip element is also capable of moving longitudinally of the frame or loop 10, within limits, and when the grip element 18 has been turned for substantially a complete revolution, it is elevated slightly and the jaw 19 will then press the

hose folded about its edge against the pad or block 14, when the jaw 19 clears the flange 17 and the grip element is released. The downward pull upon the hose tends to move the grip element 18 downwardly, thus increasing the pressure upon the hose against the block 14. The flanges 16 and 17 serve as stops for the jaw 19.

It is to be understood that the form of my invention herewith shown and described is to be taken as a preferred example of the same and that various changes in the shape, size, and arrangement of parts may be resorted to, without departing from the spirit of my invention or the scope of the subjoined claims.

Having thus described my invention, what I claim is:

1. A garment supporter comprising a frame provided near its lower end with a jaw, a grip element having a free end disposed at an elevation above the jaw when such free end presses the garment against the jaw, means arranged at an elevation above the jaw and at a point remote from the upper end of the frame to mount the grip element upon the frame so that the grip element may be turned upwardly through the upper end of the frame for substantially a complete revolution and also move longitudinally of the frame, the free end of the grip element being arranged to press the garment downwardly upon the jaw by the downward pull of the garment upon the grip element, and means to support the frame.

2. A garment supporter comprising a frame provided near its lower end with a jaw, a grip element having a free end disposed at an elevation above the jaw when such free end presses the garment against the jaw, means arranged at an elevation above the jaw and at a point remote from the upper end of the frame and connected with the grip element near its opposite end and serving to pivotally connect the grip element with the frame so that the grip element may be turned upwardly through the upper end of the frame for substantially a complete revolution and also move longitudinally of the frame, the free end of the grip element being arranged to press the garment downwardly upon the jaw by the downward pull of the garment upon the grip element, a stop element carried by the frame near the jaw and extending into the path of travel of the free end of the grip element, and means to support the frame.

3. A garment supporter comprising a frame having tubular sides and a lower channeled end, a rubber block held within the lower channeled end and serving as a jaw, a grip element having a free end disposed at an elevation above the rubber block when such free end presses the

garment against the rubber block, a pivot element arranged at an elevation above the rubber block and at a point remote from the upper end of the frame and secured to the grip element near its opposite end and slidably mounted in the tubular sides to turn therein and move longitudinally of the same, a stop element carried by the lower end of the frame and positioned upon one side of the rubber block, and means to support the frame, the arrangement being such that the grip element may be turned upwardly through the upper end of the frame from one side of the frame to the other side and held in the closed position substantially within the plane of the frame.

4. A garment supporter comprising a frame having tubular sides, said tubular sides being provided with longitudinal slots, the ends of the slots serving as stops, said frame having a lower channeled end which is arranged at an elevation beneath said slots, a rubber block held within the lower channeled end, the sides of the lower channeled end extending above the block and one side extending above the other side, a grip element having a free end disposed at an elevation above the rubber block when such free end presses the garment against the rubber block, a pivot element secured to the opposite end of the grip element and arranged above the rubber block and at a point remote from the upper end of the frame, said pivot element extending through the slots so that the free end of the grip element may be turned upwardly through the upper end of the frame from one side of the frame to the other, said pivot element being provided at its ends with heads to prevent the pivot element being withdrawn from within the slots, and means to prevent the lateral displacement of the grip element when in the lowered position.

5. A garment supporter comprising a frame provided near its lower end with a jaw, a grip element having a free end disposed at an elevation above the jaw when such free end presses the garment against the jaw, means arranged at an elevation above the jaw and at a point remote from the upper end of the frame to pivotally mount the grip element from the frame so that the free end of the grip element may be turned upwardly through the upper end of the frame from one side of the frame to the other side, the free end of the grip element being arranged to press the garment downwardly upon the jaw by the downward pull of the garment upon the grip element, and means to prevent the lateral displacement of the grip element when in the lowered position.
